UNITED STATES PATENT OFFICE.

JOSEPH D. MULLEN, OF ST. LOUIS, MISSOURI, ASSIGNOR TO TEXAS DELINTER COMPANY, LIMITED, OF SHREVEPORT, LOUISIANA, A CORPORATION OF LOUISIANA.

DELINTER.

1,068,156.

Specification of Letters Patent.

Patented July 22, 1913.

Application filed April 24, 1912. Serial No. 692,762.

To all whom it may concern:

Be it known that I, JOSEPH D. MULLEN, a citizen of the United States, residing at the city of St. Louis, State of Missouri, have 5 invented certain new and useful Improvements in Delinters, (Case A,) of which the following is a specification.

This invention relates to cotton-seed delinters, and has for its object to provide a 10 machine of the character described that is primarily intended for removing from cotton-seed all the fibers and lint which remain adhering thereto after the ginning operation, though capable, of course, of use for 15 similar purposes in the treatment of objects other than cotton-seed.

Another object of the present invention is to provide a machine having a delinting chamber in which the seeds or other objects 20 to be delinted are delinted and agitated therein solely by the delinting means, thereby obviating the use of separate means for agitating same.

Further, the present invention consists of 25 the novel features of construction and arrangements of parts, as will be hereinafter more fully described and pointed out in the claims.

In the accompanying drawings forming 30 part of this specification, in which like numbers of reference denote like parts wherever they occur, Figure 1 is a longitudinal sectional view of a delinter embodying the present invention; Fig. 2 is an end elevation 35 of same; Fig. 3 is a sectional view on the line 3—3, Fig. 1; Fig. 4 is a detailed view, on an enlarged scale, partly in section and partly in elevation, of part of a delinting cylinder; Fig. 5 is a sectional view on the 40 line 5—5, Fig. 4; Fig. 6 is a perspective view of the member for dividing the delinting chamber into a plurality of compartments; Figs. 7 and 8 are detailed views, on an enlarged scale, of the outlet valve, Fig. 8 45 being a sectional view on the line 8—8, Fig. 7; Fig. 9 is an interior elevation of one of the heads of the casing; Fig. 10 is a side elevation, on an enlarged scale, of one of the staves; and Fig. 11 is an end elevation, on 50 an enlarged scale, of same.

The casing 1 contains the delinting mechanism, and is supported by standards 2 which may be supported on a suitable base 3. The ends of the casing 1 are closed by 55 heads or castings 4, which may be supported

on standards 2, and the top of said casing is closed by a cover plate 5 or a plurality of such plates, which may be detachably secured in place by any suitable means so that either one or all of said plates may be removed, in order to permit ready access to the interior of the machine for the purpose of cleaning or repairing same or for any other purpose. The bottom of said casing 1 is preferably hopper-shaped and is provided 60 with an outlet 6 which is controlled by a gate or valve 7 of any suitable construction, the purpose of said outlet being to allow any seeds that may fall into the bottom of said casing to be removed, when the gate 7 is 65 opened. A suction pipe 8, connected to the lower part of the casing 1, is adapted to draw the lint from the interior of said casing and is connected with any suitable source of suction supply (not shown). 70

The delinting cylinders 9 are preferably arranged so that their axes of rotation are substantially parallel to each other and are disposed substantially horizontal within the casing 1, the shafts 10, which support said 75 cylinders, being journaled in openings in the heads 4. Said cylinders 9 are preferably spaced apart symmetrically, and between each two adjacent cylinders a stationary 80 stave 11 is located, the purpose of this arrangement being to form a delinting chamber 12, the walls of which are the delinting cylinders 9 and the staves 11. Each cylinder 9 is preferably formed of a metal tube 85 which is screw-threaded externally and the ends of said cylinder are secured to suitable heads 13 which are rigidly mounted on its supporting shaft 10, the periphery of the screw-threads being serrated, so as to form teeth 14 which are adapted to remove the 90 lint or fibers from the seeds that come in contact with said cylinder. The screw-threads are preferably formed with a relatively large pitch and the cylinders 9 are 95 rotated in such direction that the screw-threads thereon will have a tendency to feed the seeds from the receiving end to the discharge end of the delinting chamber. 100

At one end of the machine, each shaft 10 projects from the head 4 and bears a gear 15. 105 A gear 16 on drive shaft 17, which receives its power from any suitable source, meshes with and drives the gears 15 on shafts 10, so as to rotate the cylinders 9 in the direction indicated by the arrows, Fig. 3. The drive 110

shaft 17 extends longitudinally through substantially the middle of the delinting chamber 12, and is arranged to extend substantially horizontal and parallel to the shafts 5 10, being journaled in bearings 18 which are bolted or otherwise secured to the heads 4. An inlet spout 19 communicates with one end of the delinting chamber 12 through an opening 20 in the head 4 at one end of the 10 machine, and a discharge spout 21 communicates with the other end of the delinting chamber 12 through an opening 22 in the other head 4, said openings 20 and 22 being surrounded by flanges 23 borne by said heads 15 15. The shaft 17 extends through the inlet spout 19 and bears on Archimedean screw 24, or the like, which is adapted to rotate with said shaft, in order to feed the seeds from said spout 19 into the delinting chamber 12 through the opening 20. Said shaft 17 extends, also, through the discharge spout 21 and has a valve 25 reciprocatively mounted thereon for the purpose of controlling the passage of the delinted seeds through the 20 opening 22 from the delinting chamber 12 into the discharge spout 21, said valve being preferably disk-shaped and being substantially the same size and having the same shape as the opening 22. A sleeve 26 borne 25 by valve 25 encircles shaft 17 and contains a screw-threaded opening 27 to receive a bolt or screw 28. Said bolt or screw 28 is preferably screw-threaded only along a portion of its length, in order to fit in the screw- 30 threaded opening 27 in sleeve 26, and the end portion of said bolt or screw is left smooth and extends through an elongated slot 29 in shaft 17, which slot communicates with an opening 30 that extends longitudinally in the end of said shaft 17. The end 35 of the bolt or screw 28 projects from the slot 29 into an opening 31 in valve-stem 32, as best seen in Fig. 8, the latter being located within the opening 30 in shaft 17 and being capable of reciprocating longitudinally 40 therein. By reason of valve 25 and its stem 32 being connected by the bolt or screw 28, as just described, same are caused to rotate with shaft 17, and whenever the valve 25 is 45 moved longitudinally on shaft 17, the bolt or screw 28 causes the stem 32 to move with said valve, or vice versa. The stem 32 extends from the end of shaft 17 and the end thereof bears against the end of a screw-threaded rod 33, which passes through a 50 screw-threaded opening in bracket 34, said bracket being secured to one of the bearings 18 by a set-screw 35 or other suitable means, and said rod having a hand-wheel 36 secured thereto to afford a means for turning same. The seeds within the delinting chamber 12 55 press against the face of valve 25 and thereby tend to move said valve away from the opening 22, in order to allow the delinted seeds to pass from the delinting chamber 12

into the discharge spout 21. Such movement of valve 25 is limited by the engagement of its stem 32 with the end of rod 33, and by means of said rod the valve 25 can be adjusted with respect to the opening 22, 70 in order to allow the delinted seeds to discharge faster or slower from the delinting chamber 12, as may be desired. Said discharge spout 21 is provided with a sight-hole 37 through which the interior of said 75 spout can be observed from outside the machine. The delinted seeds discharge from the spout 21 into a suitable receptacle or conveying means (not shown).

A hollow member 38 surrounds the shaft 80 17 within the delinting chamber 12 and extends from end to end of said chamber, one end of said member terminating within the opening 20 and the other end thereof terminating within the opening 22. Each end of member 38 is preferably tapered, so as to leave a space between same and the flange 23 surrounding same, and is provided with a lug 39 or a plurality of such lugs, each of 85 said lugs being bolted or otherwise secured 90 to said flange, in order to hold the member 38 stationary. Said member 38 is provided externally with a plurality of flutes or furrows 40, which extend longitudinally thereof. The flutes or furrows 40 in member 38 95 are preferably equal in number to the delinting cylinders 9 and are substantially concentric to said cylinders. Said flutes 40 divide the delinting chamber 12 into a plurality of compartments 41 and hold the seeds 100 in engagement with the delinting cylinders 9. Each compartment 41 in the delinting chamber 12 communicates with the adjacent compartments 41 so that the seeds can pass from one compartment to another.

While, for the purpose of illustration, the delinter depicted in the drawings is equipped with four delinting cylinders 9 and four staves 11, yet, it should be understood that either a greater or a smaller number of cylinders 9 and a corresponding greater or smaller number of staves 11 may be used, if so desired. When four cylinders 9 are used, same are preferably located at substantially equal distances apart, two of 110 said cylinders being disposed on substantially the same level and being located directly above the other two cylinders, respectively, as clearly shown in Fig. 3. The staves 11 are located between the cylinders 115 9, in order to retain the seeds in the delinting chamber 12, one of said staves being arranged to close the top, another to close the bottom, and the other two to close the sides of said delinting chamber. The staves 11 at 120 125 the sides of the chamber 12 are preferably located farther away from the member 38 than the upper and lower staves 11, so that said chamber is relatively greater in width than in height and, also, so that the com- 130

partments 41 communicate through a larger space at the sides of the chamber 12 than at the top and bottom of said chamber. By this arrangement the body of seeds at each 5 side of the chamber 12 is subjected simultaneously to the action of an upper and a lower cylinder 9, with the result that said cylinders increase the agitation of the seeds, when the seeds pass from an upper compartment 41 into a lower compartment 41 at one side of the chamber 12 or when same pass from a lower compartment 41 into an upper compartment 41 at the other side of said chamber.

15 Each stave 11 is preferably formed of a plate, which may be secured to a bar 42 by bolts 43 or other suitable means, as depicted in Figs. 10 and 11, or, if desired, said stave or plate 11 may be formed integrally with 20 said bar. Said bar 42 extends from end to end of the machine, and has its ends supported in pillow-blocks 44 borne by heads 4, respectively. A cap 45 on each pillow-block is held in place thereon by bolts 46 or the 25 like, and, in turn, holds the end of bar 42 firmly in said pillow-block, so as to hold the stave 11 stationary. This arrangement allows the staves 11 to be readily adjusted, when the bolts 46 are loosened. A blade 47, 30 which extends longitudinally of the stave 11, is preferably riveted or otherwise secured to the inner face of said stave, i. e., the face that is exposed to the delinting chamber 12, and a plate 48, which, also, extends longitudinally of said stave, is fastened to the outer face of said stave by screws or bolts 49. Said screws or bolts 49 pass through elongated notches 50 in the edge of plate 48, the purpose of such arrangement being to permit transverse adjustment of said plate 48. Each stave 11 occupies an inclined position, and is so adjusted, as hereinabove described, that the beveled edge 51 of its blade 47 nearly touches 45 the teeth 14 on an adjacent delinting cylinder 9, so as to deflect the seeds from said roller, and its plate 48 is adjusted, as hereinabove described, so that an edge thereof nearly touches the teeth 14 of another cylinder 50 9 adjacent thereto, in order to prevent the seeds from falling out of the chamber 12, said cylinders 9 being rotated so that the cylinder adjacent the blade 47 moves the seeds toward said blade, and the cylinder adjacent the plate 48 moves the seeds 55 away from said plate.

A shaft 52 is preferably arranged to extend from end to end of the machine and is journaled in a bearing 53 borne by one of the heads 4 and, also, in a bracket 54, which is bolted or otherwise secured to the other head 4, being located above the upper stave 11 and having a member 55 or a plurality of such members mounted thereon so as to rotate therewith. Each member 55 is pro-

vided with a plurality of arms 56 to which the blades or plates 57 are riveted or otherwise secured. A pulley 58 borne by drive shaft 17 drives a belt 59, which, in turn, drives a pulley 60 rigidly mounted on shaft 52, thereby rotating said shaft 52 and causing the blades 57 to fan or blow the lint away from the upper stave 11. By this arrangement, the lint is prevented from accumulating on top of the upper stave 11, in 75 the space between the upper cylinders 9.

The operation of the machine is as follows: Power is applied to the drive shaft 17 from any suitable source, so as to drive the delinting cylinders 9 through the medium of gears 15 and 16. The seeds to be delinted are fed into the inlet spout 19 and are then caused by the pressure of screw 24 to pass through the opening 20 into the delinting chamber 12 and to travel toward the valve 25, so as to fill all the compartments 41. The fluted member 38 holds the seeds in the compartments 41 in engagement with the delinting cylinders 9, and the teeth 14 borne by said delinting cylinders not only remove the 90 lint from the seeds, but, also, agitate the seeds in all the compartments 41, with the result that, while the seeds are being fed through the delinting chamber 12 by the screw 24, same pass from one compartment 95 to another and thereby come in contact with the several delinting cylinders before reaching the discharge end of the delinting chamber. This agitation of the seeds in the several compartments causes each seed to come in contact with one or more of the delinting cylinders 9, with the result of removing all the short fibers or lint from each seed that passes through the delinting chamber. The pressure of the seeds within the delinting 100 chamber 12 holds the valve 25 open and thereby allows the delinted seeds to escape from said delinting chamber into the discharge spout 21. The lint or fiber that is scraped off the seeds by the teeth 14 on the 105 delinting cylinders 9 drops from said cylinders into the bottom of the casing, and is then drawn away through the suction-pipe 8.

I claim:

1. A delinting machine including a plurality of delinting cylinders arranged in spaced relation, means to close the spaces between the cylinders and to form a delinting chamber in conjunction with said cylinders, and a stationary element in the center 115 of the delinting chamber having a plurality of sides arranged so that each cylinder is disposed substantially opposite to one of the sides of said element, whereby the latter provides a stationary wall for each of a series of compartments, each of the latter 120 being formed by said stationary walls, the cylinder adjacent thereto and said closing means, and means to rotate the cylinders.

2. A delinting machine having a delinting 130

- chamber, a plurality of delinting cylinders forming a portion of the wall of said chamber, and staves intermediate of said cylinders and forming another portion of the wall of said chamber, each of said staves comprising an adjustable member, a blade having a beveled edge secured to one side of said member, and a plate adjustably secured to the other side of said member.
3. A delinting machine having a delinting chamber, a plurality of delinting cylinders forming a portion of the wall of said chamber, staves intermediate of said cylinders and forming another portion of the wall of said chamber, and a fan adapted to blow the lint from the uppermost stave.
4. A delinting machine having a delinting chamber, a plurality of delinting cylinders forming a portion of the wall of said chamber, staves intermediate of said cylinders and forming another portion of the wall of said chamber, and a stationary fluted member dividing said chamber into a plurality of communicating compartments and adapted to hold the seeds in engagement with said cylinders, the upper and lower staves being relatively closer to said member than the side staves.
5. A delinting machine having a delinting chamber, a plurality of cylinders forming a portion of the wall of said chamber, staves intermediate of said cylinders and forming another portion of the wall of said chamber, a stationary hollow member adapted to hold the seeds in engagement with said cylinders within said chamber, a drive shaft extending through said member, and means actuated by said shaft for rotating said cylinders.
6. A delinting machine having a delinting chamber, a plurality of cylinders forming a portion of the wall of said chamber, staves intermediate of said cylinders and forming another portion of the wall of said chamber, a stationary hollow member adapted to hold the seeds in engagement with said cylinders within said chamber, a drive shaft extending through said member, and means actuated by said shaft for rotating said cylinders, and means borne by said shaft for feeding the seeds into and through said chamber.
7. A delinting machine having a delinting chamber, a plurality of cylinders forming a portion of the wall of said chamber, staves intermediate of said cylinders and forming another portion of the wall of said chamber, a stationary hollow member adapted to hold the seeds in engagement with said cylinders within said chamber, a drive shaft extending through said member, and means actuated by said shaft for rotating said cylinders, means borne by said shaft for feeding the seeds into and through said chamber, and a valve reciprocatively mounted on said shaft for controlling the discharge of the delinted seeds from said chamber.
8. A delinting machine having a delinting chamber, a plurality of cylinders forming a portion of the wall of said chamber, staves intermediate of said cylinders and forming another portion of the wall of said chamber, a stationary hollow member adapted to hold the seeds in engagement with said cylinders within said chamber, a drive shaft extending through said member, and means actuated by said shaft for rotating said cylinders, means borne by said shaft for feeding the seeds into and through said chamber, a valve reciprocatively mounted on said shaft for controlling the discharge of the delinted seeds from said chamber, and an adjustable stop for limiting the movement of said valve.
9. In a delinting machine, the combination of a casing having a delinting chamber, a plurality of delinting cylinders forming a portion of the wall of said chamber, staves intermediate of said cylinders and forming another portion of the wall of said chamber, a stationary hollow member adapted to hold the seeds in engagement with said cylinders, a drive shaft extending through said member, means actuated by said shaft for rotating said cylinders, an auxiliary shaft disposed above the uppermost stave, and blades borne by said auxiliary shaft for fanning the lint away from the uppermost stave.
10. In a delinting machine, the combination of a casing having a delinting chamber, a plurality of delinting cylinders forming a portion of the wall of said chamber, staves intermediate of said cylinders and forming another portion of the wall of said chamber, a stationary hollow member adapted to hold the seeds in engagement with said cylinders, a drive shaft extending through said member, means actuated by said shaft for rotating said cylinders, an auxiliary shaft disposed above the uppermost stave, blades borne by said auxiliary shaft for fanning the lint away from the uppermost stave, and means actuated by said drive shaft for rotating said auxiliary shaft.
11. In a delinting machine having a delinting chamber and an outlet therefor, a series of delinting cylinders forming a part of the walls of said chamber, means for holding the seeds in engagement with said cylinders, a shaft having an opening in one end thereof, a valve stem reciprocably mounted in said opening, a valve for controlling the delinting chamber outlet slidably mounted on the shaft and being connected to said stem, and a screw for engagement with the outer end of said stem to limit the outward movement of said stem.
12. In a delinting machine, an annular series of spaced delinting cylinders, station-

ary hollow means in the center of the space defined by said cylinders, a shaft extending through said means, a series of means to close the spaces between said cylinders, a 5 fan above the uppermost of said last mentioned means, and means to drive said fan and cylinders simultaneously from said shaft.

13. A delinting machine including a plurality of delinting cylinders arranged in spaced substantially circular relation, means in each of the spaces between the cylinders to close same, and to form a delinting chamber in conjunction with said cylinders, and 15 a stationary element in the center of the delinting chamber having a series of sides arranged so that each side faces an adjacent cylinder to form a compartment in conjunction therewith.

20 14. A delinting machine including a plurality of delinting cylinders arranged in spaced substantially circular relation, means in each of the spaces between the cylinders

to close same, and to form a delinting chamber in conjunction with said cylinders, and 25 a stationary element in the center of the delinting chamber having a series of concave faces each of which confronts a cylinder and is substantially concentric thereto.

15. In a delinting machine, an annular 30 series of spaced delinting cylinders, stationary hollow means in the center of the space defined by said cylinders, a shaft extending through said means, a series of means to close the spaces between said cylinders, 35 means to prevent the accumulation of lint upon one of the closing means, and means operated from said shaft to actuate the means for preventing accumulation of lint.

In testimony whereof I hereunto affix my 40 signature in the presence of two witnesses.

JOSEPH D. MULLEN.
